UNITED STATES PATENT OFFICE.

FRANCIS A. WALSH, OF MILWAUKEE, WISCONSIN.

DESIGN FOR A LARD-PAIL.

SPECIFICATION forming part of Design No. 15,847, dated February 17, 1885.

Application filed January 12, 1885. Term of patent 7 years.

To all whom it may concern:

Be it known that I, FRANCIS A. WALSH, a citizen of the United States, residing at Milwaukee, in the county of Milwaukee and State 5 of Wisconsin, have invented and produced a new and original Design for Lard-Pails and Analogous Vessels, of which the following is a specification, reference being had therein to the accompanying drawings.

10 My design relates to that class of vessels known as "lard-pails," and it consists in the external configuration of said pail and its cover, whereby a pleasing artistic effect is produced, as shown in the drawings hereto annexed, in 15 which—

Figure 1 is a sectional view of my lard-pail and cover, showing the general outlines of my said design; and Fig. 2 is a perspective view of the same, illustrating my design in its entire.

20 A represents the body of the pail, which has an ornamental bead, *a*, near its upper part, below which, and opposite to each other, are two rounded bosses, *a' a'*, while the top of the body has a rounded continuous inwardly-25 rolled rim, *a''*, and the bottom of the pail has a flattened inwardly-turned rim, *a'''*, above which is a flat bottom, *a''''*.

B represents the cover of the pail, which has a vertical circular flange, *b*, having a 30 rounded top rim, *b'*, and below this a circular inner depression, *b''*, from whence rises the flat top *b''''* of the cover, the surface of the metal between the flat top and the depressed ring having a rounded beveled shape extending 35 inwardly and upward from the depressed ring *b''*, as shown at *b''''*, the said top being on a plane above the rim *b'*. The handle *C* is a little more than a semicircle in shape, with inwardly-extending ends *c c'*. 40

Having thus described and illustrated my new and original design, what I claim is—

In a design for lard-pails, the cover *B*, having vertical circular flange *b*, with rounded top rim, *b'*, inner circular depression, *b''*, rounded beveled surface *b''''* rising therefrom, and flat top *b''''* on a plane above the top of the rim *b'*, as shown. 45

In testimony whereof I affix my signature in presence of two witnesses.

FRANCIS A. WALSH.
